(57) **CLAIM**

The ornamental design for an eyeglass display, as shown and described.

DESCRIPTION

FIG. 1 is a perspective view of an eyeglass display showing my new design.

FIG. 2 is a top plan view of the eyeglass display as shown in FIG. 1;

FIG. 3 is a right side elevational view of the eyeglass display shown in FIG. 1, with the left side being a mirror image thereof;

FIG. 4 is a bottom plan view of the eyeglass display as shown in FIG. 1;

FIG. 5 is a front elevational view of the eyeglass display as shown in FIG. 1; and,

FIG. 6 is a back elevational view of the eyeglass display as shown in FIG. 1.

The broken lines are for illustrative purposes only and form no part of the claimed design.

1 Claim, 4 Drawing Sheets
